METHOD OF MAKING BUFFERS

John W. Marsh, Arlington, Va.

Application September 11, 1946, Serial No. 696,315

2 Claims. (Cl. 29—164)

1

This invention relates to a method of buffers for railway rolling stock and is concerned more particularly with a method by which buffers can be made at low cost.

For a better understanding of the invention, reference may be made to the accompanying drawing, illustrating the new method of making buffers. In the drawing,

Fig. 1 is a view in longitudinal section of a buffer made in accordance with the present invention;

Fig. 2 is a view in longitudinal section through parts of the buffer at one stage in its manufacture; and

Fig. 3 is a view similar to Fig. 2 showing the final manufacturing operation.

The buffer illustrated in Fig. 1 comprises a housing 10, which is preferably of hollow cylindrical form and has opposite end portions 10a and 10b of different diameter and separated by a generally radial shoulder 11. The housing can be made from a length of seamless tubing by ordinary swaging operations.

A plunger 12, also made from seamless tubing, is mounted within the housing with a sliding fit and it includes opposite end portions 12a, 12b of different diameter separated by a generally radial shoulder 13. The small end portion 12a of the plunger is longer than the small end portion 10a of the housing, and the large end portion 12b is shorter than the large end portion 10b of the housing. Accordingly, when the plunger is inserted within the housing with its large and small diameter end portions within the corresponding end portions of the housing and the shoulders on the plunger and housing in contact, the small end portion 12a of the plunger projects outwardly beyond the end of portion 10a of the housing, and the end of portion 12b of the plunger lies inward from the end of portion 10b of the housing.

In the completed buffer, the large end of the housing and the small end of the plunger are provided with closures, and resilient means within the plunger and housing act on the closures to hold the plunger and housing normally with their shoulders in contact and to resist movement of the plunger farther into the housing. In the buffer illustrated, the large end of the housing is closed by a base plate 14 and, in the manufacture of the housing, the small end of the plunger is inserted within the large end of the housing

2

and the plunger is moved lengthwise within the housing until the shoulders of the plunger and housing are in contact. The plate 14 is then applied to the large end of the housing and secured in place by welding indicated at 15. The resilient means, which may be a coil or volute spring or rubber springs separated by spacers, are then inserted into the plunger and housing through the small end of the plunger to bear against the inner face of the plate 14. In the buffer illustrated, the resilient means take the form of a coil spring 16, which has a length, when uncompressed, which is longer than the overall length of the plunger and housing, when their shoulders are in contact.

Accordingly, when the spring is inserted in the plunger and housing until one end engages the inner face of the plate 14, the other end of the spring projects out of the small end of the housing.

After insertion of the spring as described, a head 17, which is substantially larger in diameter than the housing and preferably of dished formation, is to be secured to the small end of the plunger to confine the spring under compression. For this purpose, the assembled parts are placed in an apparatus, such as a press, which includes relatively movable members 18 and 19, with the base 14 bearing against one of the members. The head is then inserted between the other member and the end of the spring projecting out of the plunger. Pressure is next applied through the plate and head to compress the spring until the large end of the plunger seats against the inner face of the base, whereupon the head is welded to the small end of the plunger as indicated at 20, the compression on the spring being maintained through the welding operation. After the welds have set, the buffer is removed from the press and the expansion of the spring forces the plunger outwardly from the housing until the shoulders on the plunger and housing engage.

Since the uncompressed length of the spring is greater than the overall length of the plunger and housing when their shoulders are in contact, the spring is under compression at all times and tends to resist any movement of the plunger into the housing. The initial resistance of the buffer depends upon the pre-compression of the spring, that is, the extent to which the spring has been compressed to make its length equal to the overall length of the plunger and housing when their

shoulders are in contact. The travel of the buffer is determined by the distance between the large end of the plunger and the inner face of the base, when the shoulders on the housing and plunger are in contact. Both the initial resistance and the travel of the buffer may be varied, as desired, within relatively wide limits.

I claim:

1. A method of making a buffer for railway rolling stock including a hollow housing and a hollow plunger each formed of a length of seamless tubing flaring between its ends to produce opposite end portions of different diameter separated by generally radial shoulders, the end portions of the plunger having an external diameter slightly less than the internal diameter of the corresponding portions of the housing and the small end portion of the plunger being longer and the large end portion of the plunger being shorter than the corresponding end portions of the housing, closures for the large end of the housing and the small end of the plunger and resilient means having a length, when uncom-pressed, which is longer than the overall length of the housing and plunger when they are dis-tended with their respective shoulders in en-gagement, within the housing and plunger acting on the closures to resist movement of the plunger into the housing, which comprises plac-ing the plunger within the housing with the large and small end portions of the plunger lying within the corresponding end portions of the housing, then welding a base plate to the large end of the housing to close that end thereof, then inserting the resilient means through the small end of the plunger into the plunger and hous-ing, then placing a head upon the projecting end of the resilient means, then applying pressure to the base plate and to the head to compress the resilient means until the large end of the plunger engages the base plate, and finally welding the head to the small end of the plunger while the large end of the plunger is maintained in en-gagement with the base plate.

2. A method of making a buffer for railway rolling stock including a hollow housing formed of a length of seamless tubing and having op-posite end portions of different diameter sep-arated by a generally radial shoulder, a hollow plunger formed of a length of seamless tubing and having end portions of different diameter, the end portions of the plunger having an ex-ternal diameter slightly less than the internal

diameter of the corresponding portions of the housing and the small end portion of the plunger being longer and the large end portion of the plunger being shorter than the corresponding end portions of the housing, clos-ures for the large end of the housing and the small end of the plunger and resilient means having a length, when uncom-pressed, which is longer than the overall length of the housing and plunger when they are distended with their respective shoulders in engagement, within the housing and plunger acting on the closures to resist movement of the plunger into the hous-ing, which comprises placing the plunger within the housing with the large and small end portions of the plunger lying within the correspond-ing end portions of the housing, then welding a closure member to the outer end of one of said housing and plunger to close that end of the same, inserting the resilient means within the plunger, then placing a second closure mem-ber against the outer end of the other of said housing and plunger, then applying pressure to both of said closure members to compress said resilient means until the large end of the plunger enga-ges the closure for the outer end of the housing, and finally, while said pressure is main-tained and the large end of the plunger is in engagement with the closure for the outer end of the housing, welding said second closure mem-ber to the outer end of said other of the housing and plunger to close the same.
